UNITED STATES PATENT OFFICE.

CYRUS L. BUNDY, OF EAST ORANGE, NEW JERSEY.

CAR-DIAPHRAGM-HOOD CONSTRUCTION.

1,145,859.

Specification of Letters Patent. Patented July 6, 1915.

Application filed May 2, 1914. Serial No. 835,790.

To all whom it may concern:

Be it known that I, CYRUS L. BUNDY, a citizen of the United States, residing at East Orange, in the county of Essex and State of New Jersey, have invented certain new and useful Improvements in Car-Diaphragm-Hood Constructions, of which the following is a specification.

The invention has for its object the provision, in combination with an expandible car diaphragm of the ordinary construction, of a hood or shield therefor to prevent the lodgment thereon of the heavier live coals and hot cinders whereby the diaphragm fabric would be burned and thus destroyed; also to protect material of the diaphragm folds from snow and rain charged with grit which would otherwise fall thereon and enter within the seams rotting the fabric and cutting the threads of the same.

In car construction generally, the flat roof diaphragm as distinguished from the peak roof has been found to be the more desirable, but by reason of the necessity for shedding the snow and rain a lateral pitch has to be given the roof or a supplemental roof or hood provided spaced from and above the roof proper. These hoods have been made in the same way as the roof, of fabric folded to expand and contract with the diaphragm, and have a lateral pitch to discharge the moisture to the sides. It has been demonstrated, however, that the larger live coals falling upon such hoods catch in the folds and burn holes in the fabric thus speedily destroying the usefulness of the same.

According to the present construction a shield or upper hood of metal is arranged above the diaphragm roof proper or above the usual type of supplemental roof or hood, if such latter be employed. This metallic shield is hinged at one end and slidably mounted at the other so as to accommodate itself by longitudinal movement to the expansion and contraction of the diaphragm and it preferably has a lateral or longitudinal pitch. The upper surface of the metal shield being smooth, however, cinders falling thereon will not collect in any case but will be blown off by the gusts of air due to the movement of the train and will fall clear of the underlying fabric of the diaphragm.

In order that the invention and its man-

ner of application may be readily understood a preferred embodiment of the same is set forth in the accompanying drawing and in the subjoined detailed description based thereon. As, however, the invention is capable of constructional modification within a wide range the drawing and description are to be taken in an illustrative and not in an unnecessarily limiting sense.

In the drawing—Figure 1 is an end elevation of the upper portion of a railway car having the invention installed therein; Fig. 2 is a side elevation partly in longitudinal vertical section illustrating the mounting of the shield; and Figs. 3 and 4 are views similar to Figs. 1 and 2 respectively, but showing another embodiment of the invention.

Having particular reference to the first embodiment of the invention illustrated, the face plate of the diaphragm construction is represented at 11, connected by the usual expandible diaphragm with the end plate 12 of the car body indicated generally at 13, the diaphragm comprising the two vertical legs 14 and the horizontal roof 15 made of fabric with bellows folds. Above the roof 15 may or may not be arranged a supplemental roof of fabric as is common, or the roof 15 may itself be omitted. To the face plate 11 along its upper edge is hinged at 16 a metal shield 17 having preferably a smooth upper face. The shield 17 as illustrated, extends at an upward inclination and has its free end 18 slidably mounted within a space 19 and resting upon the inclined surface 20 of the deck end 21 of the car roof, the space 19 being covered by a supplemental deck roof portion 22 between which and the deck roof 20 the free upper end of the shield 17 is housed. The shield 17 has a width coextensive with or slightly greater than the roof 15 of the diaphragm so as to prevent the larger live coals from falling upon the roof proper or supplemental roof of the diaphragm.

It will be observed that as the shield is hinged at one end to the face plate and at its other end is free to slide longitudinally of the car the expansion and contraction of the diaphragm is not interfered with in any degree and the fabric of the diaphragm is protected from the lodgment thereon of hot cinders which would otherwise burn holes

in the same and speedily destroy its usefulness.

That embodiment of the invention illustrated in Figs. 3 and 4 possesses the same general characteristics as that hitherto described but the shield itself is of a somewhat modified form being provided near its lower edge with a trough 23 having a lateral pitch whereby the water falling upon said shield is discharged at 24 upon each side free of the underlying diaphragm construction. That portion of the shield above the trough is likewise curved in a lessening degree as indicated at 25 and at its upper edge the cross sectional contour of the shield corresponds preferably to that of the roof 20 upon which it slides.

I claim:

- 20 1. The combination in a car diaphragm construction of a metallic shield arranged above the diaphragm roof in spaced relation thereto, said shield flexibly secured at one end and slidable at the other longitudinally of the car, substantially as described.
- 25 2. The combination in a car diaphragm construction of a metallic shield arranged above the diaphragm roof in spaced relation thereto, said shield hinged at one end and slidable at the other longitudinally of the car, substantially as described.
- 30 3. The combination in a car diaphragm construction of a metallic shield arranged above the diaphragm roof in spaced relation thereto, said shield hinged at its forward end and slidable relatively to the car at its rear end, substantially as described.
- 35 4. The combination in a car diaphragm construction of a metallic shield arranged above the diaphragm roof in spaced relation thereto, said shield having a downward pitch longitudinally of the car and hinged at its lower end to the face plate of the dia-

phragm construction and slidable within the car roof at its upper end, substantially as described.

45 5. The combination in a car diaphragm construction of a metallic shield arranged above the diaphragm roof in spaced relation thereto, said shield having a downward pitch longitudinally of the car and providing near its lower end a transversely extending trough with a lateral pitch, the shield hinged at its lower end to the face plate of the diaphragm construction and slidable at its upper end within a housing 50 upon the car roof, substantially as described.

55 6. In a car vestibule construction including a car end, a face plate movable relative thereto, and diaphragm side walls extending between the car end and face plate, a metallic cover overlying the space between the car end and face plate and the side walls and separate from said walls, said cover flexibly secured at one end and slidable at the other 60 longitudinally of the car.

65 7. In a car vestibule construction including a car end, a face plate movable relative thereto, and diaphragm side walls extending between the car end and face plate, a metallic cover overlying the space between the car end and face plate and the side walls and separate from said walls, said cover hinged at one end to the face plate and 70 slidable at the other end longitudinally of the car.

75 In testimony whereof I have hereunto signed my name in the presence of two subscribing witnesses.

CYRUS L. BUNDY.
